UNITED STATES PATENT OFFICE

134,893

DESIGN FOR A ROTARY POLISHING AND BURNISHING MACHINE

William Russell Redd, Western Springs, Ill., assignor to Power Tools, Inc., Chicago, Ill., a corporation of Illinois

Application June 8, 1942, Serial No. 107,159

Term of patent 14 years

To all whom it may concern:

Be it known that I, William Russell Redd, a citizen of the United States, residing at Western Springs, in the county of Cook and State of Illinois, have invented a new, original, and ornamental Design for a Rotary Polishing and Burnishing Machine, of which the following is a specification, reference being had to the accompanying drawing, forming part thereof.

In the drawing,

Fig. 1 is a view in perspective of a rotary polishing and burnishing machine embodying my new design; and

Fig. 2 is a top plan view thereof.

I claim:

The ornamental design for a rotary polishing and burnishing machine, as shown.

WILLIAM RUSSELL REDD.
